 tion of Maine

Application December 1, 1942, Serial No. 467,489

8 Claims. (Cl. 57—96)

This invention relates to roving machines, and more particularly to that portion of such machines by which variable rotary motion is given to the spindles and their bobbins and a variable traversing motion is given to the lifter rail upon which the bobbins are carried.

Roving machines as heretofore constructed have usually been provided with a variable speed driving mechanism for driving the spindles and the bobbins carried thereon at variable speeds comprising two relatively long tapered cone drums disposed one above the other and connected by a driving belt which is advanced along the coned surfaces of the drums upon reversal of the lifter rail at the end of each traverse of the lifter rail so that the speed of the bobbins changes automatically and simultaneously with the reversal of the lifter rail at the end of each layer of material wound on the bobbins. The top or driving cone drum usually is formed with a concave surface and driven at constant speed from the main shaft of the machine. A gear train from the top cone drives the drawing rollers of the machine, the front pair of rollers of which deliver the attenuated textile material to the flyers associated with the bobbin spindles.

The bottom or driven cone drum usually is formed with a convex surface and partakes of a variable rotational speed during the shifting movement of the cone belt longitudinally of the cone drums from one end to the other that accompanies the reversals of the lifter rail at the end of each layer of strand material laid on the bobbins. The coned surfaces of the top and bottom cone drums are always so shaped that the speed of the bottom cone drum varies inversely as the bobbin diameter. This change in rotational speed of the bottom cone drum is necessary since the number of winding revolutions per minute of the bobbins must be reduced in direct proportion to the increase in bobbin diameter, the product of bobbin diameter and winding revolutions remaining constant. The gearing is so arranged that the variable rotary motion of the bottom cone drum driving through an epicyclic gear train, known as a differential motion, regulates the winding speed of the bobbins to give them the necessary winding speed as the bobbins increase in diameter.

This prior and normal method of drive of the roving frame bobbins at variable winding speeds although satisfactory insofar as accomplishing the necessary variable regulation of the bobbin winding speed, nevertheless is found to possess certain objectionable features which frequently

introduce serious defects in the quality of the roving on the bobbins, as is well known. For example, non-uniform or improper tension of yarn from the front drawing rollers to the bobbins frequently occurs due to slippage of the cone belt during its advance along the cone drums. Also, this method of drive invites tampering with the setting of the tension mechanism by the roving machine operator instead of making the correction of the tension at the twist gear. Furthermore, the cone drums are bulky and occupy considerable valuable space within the framework of the machine, and are of expensive construction.

It is accordingly an object of the present invention to provide an improved variable speed driving mechanism that will take the place of the aforementioned concave and convex cone drums and will serve the same purpose as such prior mechanism without its disadvantages.

Another object of the invention is the provision in a roving frame organization of a variable speed driving mechanism including driving and driven expandible pulleys connected together by a V-belt, each pulley being formed of a pair of conical members one of which is fixed and the other shiftable, and a control cam connected to the shiftable member of each pulley in which the arrangement is such that the control cam is revolved intermittently by the rack gear of the builder motion and will be actuated simultaneously with the reversal of the lifter rail and the shortening of the traverse of the lifter rail whereby the shiftable members of both pulleys will be automatically adjusted together to vary, step by step, the effective diameters of the pulleys so as to decrease the speed of rotation of the bobbins as their diameters increase.

A further object of the invention is to provide in a speed varying organization of the above-described character a control cam which is so shaped and arranged as to regulate the effective diameters of the expandible pulleys to produce the same speed variation effect on the bobbins as that obtained by means of the concave and convex cone drums which is the common speed varying device in roving frames for driving the bobbins and their carriage.

A still further object of the invention is to provide in a variable speed driving mechanism of the above-described character, novel arrangements of elements which will provide a simple and compact construction capable of being manufactured at small cost, which will result in efficient operation, and which will reduce to a mini-

mum any possibility of wear which might result in uneven or improper operation of the various elements of the mechanism.

With these and other objects in view, the invention consists of certain novel features of construction and combinations of elements as will be more fully described in the following specification, and particularly pointed out in the appended claims.

In the accompanying drawings:

Fig. 1 is a front elevation of so much of the operative portion of one common type of roving frame as is necessary to illustrate the nature of the present invention and its relation to the usual operating parts of the mechanism for varying the speed of the bobbins and the builder motion;

Fig. 2 is a front elevation on a larger scale than Fig. 1 of the portion of the roving frame incorporating one form of variable speed driving mechanism according to the present invention, showing the expandible pulleys in one operating position;

Fig. 3 is a front elevation of the variable speed mechanism shown in Fig. 2 with the lower driven expandible pulley being represented in a raised position to slacken the driving belt connection and render inoperative the upper driving expandible pulley;

Fig. 4 is a detail view, partly in section, showing the arrangement and construction of the expandible pulleys and the cam mechanism associated therewith for moving the shiftable wheel members of each pulley;

Fig. 5 is a view taken on the line 5—5 of Fig. 4;

Fig. 6 is an end view of one of the conical wheels of an expandible pulley;

Fig. 7 is a detail view, observed from the underside, of the cam for imparting the variable adjusting motion to both shiftable wheel members of the expandible pulleys for varying the speed of the bobbins;

Fig. 8 is a vertical section taken on the line 8—8 of Fig. 3 showing the gearing connecting the lower expandible pulley to the differential motion; and

Fig. 9 is a diagrammatic view of the gearing incorporating the expandible pulleys of the present invention by which variable motion is imparted to the bobbin spindles and to the lifter rail carrying the bobbins.

As the general construction and operation of roving frames or speeders are well known and familiar to those skilled in the art it will be necessary here to illustrate and describe only the elements of the machine directly concerned with the present invention.

In the drawings, wherein for the purpose of illustration is shown a preferred embodiment of the invention, there is represented one common type of roving frame or speeder the general arrangement of which is shown in Fig. 1 and comprises one of the machine end frames 10, intermediate samsons 11, and the roller beam 12 which extends longitudinally of the machine at the front of the latter and is attached to the fixed framework of the machine.

Bobbins 14, of which only one is shown in the present drawings, rotatably mounted on the lifter rail or carriage 15 are given a rising-and-falling motion in the usual and well-known manner between the depending arms 16 and 17 of the flyers 18 which are suitably attached to the top of the long upright spindles 19. The lifter rail 15 in practice extends longitudinally of the

machine for substantially its entire length, and carries thereon the usual fixed bolsters (not shown) and the short loose sleeves (not shown) that surround the lower end of the bolster, all of which structure is common and well known in the art.

The spindles 19 are driven by the bevel gears 20 and 21 that receive power from a long spindle shaft 22 running the whole length of the machine. There are two lines of upright spindles 19 and two spindle shafts 22 parallel to each other and driven one from the other and receiving their power through a chain and sprocket drive 24 from the main drive shaft 25 which is driven by the multiple V-belt sheaved pulley 26 attached to the shaft 25. Power is transmitted from a motor 27 to the pulley 26 by means of a multiple V-belt sheaved pulley 28 on the motor shaft and a plurality of V-belts connecting the pulleys 26 and 28. The main drive shaft 25 transmits rotary motion through the gears 30, 31, 32 and 33 to the upper horizontal shaft 35 for driving one of the expandible pulleys of the variable speed driving mechanism of the present invention as will be more fully described hereinafter, and from the gear 33 through the gear 36 to drive the lower front fluted drawing roller 37. The lower middle and back drawing rollers 38 and 39 are arranged parallel to the front roller 37 and are driven therefrom by suitable gearing in a manner well known in the art.

The bobbins 14 are driven through beveled gears 40 and 41 and by silent chains 43 and 44 from a sleeve 45 which turns loosely on the main drive shaft 25. The sleeve 45 is driven from the shaft 46 through the differential motion 47 and the gear train composed of gears 48, 49 and the pinion 51 attached to the shaft 46. The shaft 46 is given variable rotary motion by the other expandible pulley of the variable speed driving mechanism of the present invention driven at varying rotational speeds by the expandible pulley on the shaft 35 as will be more fully described hereinafter.

The bobbins 14 have an up and down motion between the flyer arms 16 and 17, by which the yarn is traversed or laid evenly upon the barrel of the bobbin, and the up and down traversing movement of the bobbins 14 is secured by mounting them in two parallel rows upon the lifter rails 15 the connected parts of which form a carriage which is given an upward and downward motion by a rack 55 and a pinion 56 fast on a shaft 57. The shaft 57 is driven through the intermediate shaft 58 and connecting gearing from the shaft 60 on which are affixed the elongated spur gear 61 and the beveled gears 62 and 63 which are alternately brought into engagement with the beveled pinion 64 on one end of a shaft 65. The variable rotational motion of the shaft 46 also is transmitted to the shaft 65 which is driven through the gear 50 meshing with gear 49, gears 66 and 67 and bevel gears 68 and 69 from the pinion 51 on the shaft 46.

When the bevel gear 62 is in engagement with the bevel gear 64, the traversing bobbin rail 15 will be moved in one direction, and when the bevel gear 63 is in engagement with the bevel gear 64 the rail will be moved in an opposite direction, and the alternate engagement of the bevel gears 62 and 63 with the bevel gear 64 is accomplished by longitudinally sliding the shaft 60 backwards and forwards in its bearings by means of the sliding bar 71 and forks 72 engag-

ing collars 13 attached to the shaft 60. The sliding bar 71 is moved by a reversing mechanism (generally indicated at 75) by which the movement of the bar 71 is automatically reversed when the bobbin lifter rail 15 has reached the limit of its highest or lowest movement. Reversing mechanisms of various kinds are in common use in roving machines of this class and are of well known construction to those skilled in the art, and as the traversing mechanism "per se" forms no part of the present invention it is therefore deemed unnecessary to illustrate or describe the same in detail.

The winding of the yarn on the bobbin is effected by running the bobbin at a slightly higher speed than the flyer. This method of wind, which is known as "bobbin lead" wind, is almost universally used in cotton roving frames. With the "bobbin lead" wind it is evident that as the flyer speed is constant, the surface velocity of the bobbins must also be constant, that is, the winding point on the bobbin must always be maintained a certain distance in advance of the foot of the flyer. As yarn is wound upon the bobbin its size is increased and it becomes necessary to correspondingly decrease the speed of the bobbin so that the yarn will not be wound upon the bobbin any faster as the bobbin fills with yarn and increases in size since the sliver is delivered at a uniform speed from the front rolls and therefore the surface speed of the bobbin must be exactly the same under all conditions as the surface speed of the delivery rolls in order to take care of the sliver as fast as it is delivered from the front rolls. It is evident also that the yarn must be wound on the bobbin at uniform speed in order to maintain a uniform tension in the twisted yarn. To accomplish these objectives, it is necessary to gradually reduce the number of revolutions of the bobbin as it fills with yarn, and this is brought about through the differential motion 47 which, in the past, has been driven by one of the cone drums of the aforementioned prior speed-varying mechanism but, in the present instance, is driven at variable rotational speeds from one of the expandible pulleys of the variable speed driving mechanism of the present invention hereinafter to be described.

As previously mentioned, the reduction of the speed of the bobbin as its diameter increases has heretofore been accomplished by the employment of two cone drums connected by a belt which is moved along the drums by means of a rack-and-pinion mechanism actuated by a vertical shaft the rotation of which is effected by a weight so that the rotation of this shaft will cause the belt which connects together the two conical drums to be pushed along from the larger to the smaller end of the driving drum. It has been found necessary in practice to make one of the drums with its periphery slightly concave and the other drum with its periphery slightly convex in order to secure the requisite variation in the speed of the driven drum.

In accordance with the present invention I provide a novel variable-speed driving mechanism for automatically varying the speed of the bobbins comprising two expandible pulleys arranged one above the other on parallel shafts and connected by an edge active driving belt whereby power will be transmitted from one shaft to the other. Each of the expandible pulleys consists of opposed intermeshing coned wheel members, one of which is fixed and the other shiftable. A further feature of the invention comprises means

including a cam for automatically operating the shiftable pulley elements to simultaneously vary the effective working diameters of the pulleys and this cam is so constructed and arranged that the same variation in the speed of the driven expandible pulley will be secured and communicated to the bobbins as that now obtained by the usual concave and convex conical drums in present type roving machines.

In the embodiment illustrated the variable speed driving mechanism is shown as comprising the expandible pulleys generally designated 80 and 81 which are mounted in an operative relation on the parallel shafts 35 and 46 respectively. The expandible pulleys 80 and 81 are of similar construction so that the description of one will suffice for the other. Referring particularly to Fig. 4 of the drawings, the expandible pulleys are shown as being composed of two wheel members 83 and 84 each of which is substantially frusto-conical in shape with their conical side faces arranged in confronting relationship and slotted longitudinally to provide the tapering peripheries of the wheel members with a series of fingers 85 separated by open spaces 86 (see Fig. 6). The fingers 85 are rigidly connected to the annular rim or base 87 of each wheel member. The wheel members 83 and 84 of the respective pulleys 80 and 81 are mounted on the shafts 35 and 46 respectively with the fingers 84 of one wheel member entering and having interengaging relation with the slots 86 of the opposite wheel, coupling the wheel members of each set together when they are telescoped together during their operation, as hereinafter described.

The wheel members 83 are fixed to their respective shafts 35 and 46, and the wheel members 84 are slidably arranged so as to be shiftable thereon toward and away from the fixed wheel members 83 so that by moving the wheel member 84 along its particular shaft, the effective working diameter of the expandible pulley may be increased or diminished. The expanding pulleys 80 and 81 are shown connected together by means of an edge active driving belt 88 which may be V-shape in cross section to provide suitable side friction faces for engaging the confronting conical faces of the wheel members 83 and 84 of each expandible pulley. In order to adjust the diameters of the expandible pulleys 80 and 81 automatically whereby the same variation in speed of driven pulley 81 is secured as now obtained by the usual concave and convex cone drums aforementioned, provision is made for automatically operating the expandible pulleys simultaneously and in response to the change in the direction of traverse of the bobbin rail at both extremes of its stroke.

This is accomplished by moving the shiftable wheel member 84 of the upper expandible pulley 80 away from the fixed wheel member 83 thereof so as to increase the gap of the V-groove formed by the conical sides of these two wheel members and enable the V-belt 88 to descend more deeply therein. Simultaneously with this widening action of the two wheel members of the upper expandible pulley 80 there occurs a decreasing in the gap between the confronting conical sides of the two wheel members 83 and 84 of the lower expandible pulley 81.

The shiftable wheel members 84 of the upper and lower expandible pulleys 80 and 81 respectively are connected by arms 90 and 91 to a horizontal slide 92 which is suitably arranged for longitudinal reciprocation in the sams

11 of the framework of the machine. The two shiftable wheel members 84 are moved together in the same direction by the reciprocation of the slide 92 which is actuated by means of a cam 95 fastened to the underside of a gear 96. The cam 95 is slotted as indicated at 97 (see Fig. 7) and connected with the slide 92 by a pin 98 which is fixed in a bracket 99 attached to the slide 92, and the pin 98 projects into the slot 97 of the cam through an elongated slot 99' formed in a horizontal plate member 100 which is positioned above the slide 92 out of contact therewith and suitably secured to the upright channel 101 of the framework of the machine. The cam 95 and its associated gear 96 are rotatably mounted upon a stud 102 secured to the plate member 100 and are rotated by a pinion 103 which meshes with the gear 96 and is fast to one end of the vertical shaft 105 connected with and operated by the pawl and ratchet wheel escapement of the usual reversing mechanism of the machine and generally indicated at 75.

The escapement mechanism 75 is intermittently released by the action of the reversing mechanism so as to allow the weight 108 to move the vertical shaft 105, and both the reversing and escapement mechanisms are in common use in roving frames, and they are therefore not described herein in detail, as they form no part of the present invention other than providing the automatic control means for intermittently operating the expandible pulleys.

All the operative mechanism between the bobbin 14 and the differential 47 together with the reversing mechanism by which the shaft 60 is moved back and forth in order to reverse the motion of the traversing rail 15, the vertical shaft 110 carrying a drum 112 acted upon by the weight 108 and the escapement mechanism 106 connected therewith, are already in common use and well known, and their construction and operation will be clearly understood by all who are conversant with machines of this class.

In Fig. 7 the slot 97 in the cam 95 is so shaped in its longitudinal extent that the intermittent and progressive rotation of the cam in moving the pin 98 from one end to the other of the slot 97 will produce a varying adjusting movement of the slide 92 and the shiftable wheel members 84 of the expandible pulleys 80 and 81 so as to secure the same variation in the speed of the bobbin 14 as now secured by the usual concave and convex cone drums of the common variable speed mechanism generally employed for this purpose.

When the winding cycle is completed, the machine is stopped which action is effected automatically by an upright finger 115 adjustably mounted on the gear 96 and movable therewith as the gear rotates whereby the finger will strike the arm 116 of the pivoted lever 117 which will be rocked to cause its other arm 118 to push the locking piece 120 of the stopping mechanism sideways sufficiently to disengage the tooth 121 thereof from the marginal portion of a slot 122 formed in the plate member 100 whereby the locking piece 120 thus released will drop through the slot and set in motion the automatic stopping mechanism of the machine.

It is to be understood that the control cam 95 for regulating the expandible pulleys 80 and 81 to effect a change in speed of the bobbins is revolved intermittently to impart step-by-step movement of the slide 92, so that operation of the cam 95 occurs only during the period when the

builder motion becomes operative, which is at both ends of the stroke of the bobbin rail 15 to produce shortening of the layer. Furthermore, the finger 115 forming the stop for actuating the 5 automatic stopping mechanism of the machine is suitably secured to the gear 96 (see Fig. 5), and capable of manual adjustment about the stud 102 for positioning in different angularly adjusted positions where it may become effective at various selected positions during the rotation of the cam 95.

Means are provided whereby the operator may render inoperative the belt connection between the expandible pulleys 80 and 81 manually at any time during the operation of the machine, and without stopping the machine, when either the filling of the bobbins is completed or whenever it is desired to stop the rotation of the bobbins during winding. In Figs. 2 and 3 there is illustrated in detail my preferred means for attaining the above-mentioned result, in which instance, the lower shaft 46 together with the expandible pulley 81 thereon is lifted bodily from its normal working position as shown in Fig. 2 and held in an elevated and inoperative position shown in Fig. 3 thereby disengaging the driving connection of the V-belt 88 with the coned wheels 83 and 84 of the lower expandible pulley so that the belt 88 will run slack and no drive of the pulley 81 thereby will take place.

Referring now to Figs. 2, 3 and 5, it will be seen that the shaft 46 carrying the expandible pulley 81 is suitably journaled in bearing stands 125 which are mounted for pivotal movement vertically and suitably attached to the framework of the machine. As illustrated in Fig. 5, the bearing stands 125 (which, in the present embodiment of my invention, comprises two members of which only one is illustrated in this figure) is mounted 35 at the outer end of arms 126 which are attached by brackets 127 loosely mounted for pivotal movement on a horizontal rod 128 fixed at its opposite ends in brackets 129 suitably attached to upright frame elements of the machine, the rod 128 providing the pivot for the arms 126 being positioned behind and parallel to the shaft 46.

A cam 130 is keyed, pinned or otherwise secured to the lower end portion of a vertical shaft 131 journaled in the brackets 132 and 132'. The cam 130 consists of a curved plate spaced from shaft 131 and formed with a reversely curved slot 133 which is shown as being obliquely disposed with respect to the axis of the shaft 131. A cam roller 134 extends into and cooperates with the slot 133, the cam roller 134 being suitably mounted for free rotation on the outer end portion of a finger 135 which projects forwardly from and is attached to the underside of the arm 126 supporting the bearing stand 125 proximate to the shaft 131. The slot 133 in the cam 130 preferably is so shaped and disposed as to produce rapid raising of the shaft 46 and its associated pulley 81 during movement of the cam roller 134 through the longitudinal extent of the inclined portion of the slot 133. The slot 133 terminates at its upper end in a notch 136 into which the cam roller 134 enters for holding the shaft 46 and its associated pulley 81 in elevated position. Manual movement of the shaft 131 by the operator in the opposite direction will force the cam roller out of the notch 136, thence down the slot 133 to the bottom end thereof to lower the shaft 46 and the expandible pulley 81 and establish driving connection of the pulley 81 with the V-belt 88.

In the embodiment illustrated, and described above, the parts are so arranged that when the bobbin rail 15 is in its lowest position the wheel sections of the lower expandible pulley 81 will be fully telescoped, while those of the upper expandible pulley 80 will be open to provide expansion. Furthermore, as progressive shortening of the stroke of the rail takes place due to the action of the usual builder motion there also occurs simultaneously therewith changes in the bobbin speed so as to produce the same linear take-up on the bobbins as is obtained when the bobbin packages were of smaller diameter.

In accordance with the present invention many advantages are obtained over the use of previous mechanisms employing the concave and convex cone drums, among which advantages are the following: (1) maintenance of uniform tension of yarn from the draft rollers to the bobbins during winding; (2) more compact mechanism requiring less space within the machine framework; (3) no stoppage of the V-belt connecting the two expandible pulleys for driving the lower pulley from the upper pulley; and (4) less wear on this V-belt connection since it is of the edge-active type.

I claim:

1. In a roving frame, the combination with the bobbins of the machine of a variable speed mechanism for driving said bobbins comprising driving and driven expandible pulleys disposed in spaced relationship one above the other, each of said expandible pulleys consisting of two cooperating wheel members one of which is fixed and the other shiftable toward and away from said fixed wheel member, the wheel members forming each pulley being connected together in all positions of adjustment of the shiftable wheel member, an edge active belt providing a driving connection between said expandible pulleys for driving one pulley from the other, a slide, connections between said slide and the shiftable wheel member of each expandible pulley, means including a cam actuated intermittently by the usual builder motion of the machine and operable only during the reversal of stroke of the traversing bobbin rail in the opposite direction for moving both of said shiftable wheel members simultaneously relative to their associated fixed wheel members to vary the speed ratio between said driving and driven expandible pulleys, and intermediate connecting mechanism whereby the rotation of said driven expandible pulley is communicated to the bobbins of the machine.

2. In a roving frame, the combination with the bobbins of the machine of a variable speed mechanism for driving the bobbins comprising driving and driven expandible pulleys each consisting of two coaxing conical wheels one of which is fixed and the other shiftable axially toward and away from the fixed wheel of the set, the confronting sides of the opposed wheels being so constructed and arranged that the wheels of each pulley have interlocking and telescoping connection in all adjusted positions of the shiftable wheel members, a belt providing a driving connection between said pulleys, intermediate connecting mechanism between said driven expandible pulley and the bobbins of the machine, a slide, connections between said slide and said shiftable wheels, a rotatable cam operatively connected to said slide for actuating the same, and means responsive to the step-by-step adjusting movements of a builder motion of the intermittent type for revolving said cam to effect step-by-step adjustment of said slide through a distance sufficient to adjust the shiftable wheels of both expandible pulleys.

3. In a roving frame, the combination with the bobbins of the machine of a variable speed mechanism for driving the bobbins comprising driving and driven expandible pulleys each consisting of two coaxing conical wheels one of which is fixed and the other shiftable axially toward and away from the fixed wheel of the set, the confronting sides of the opposed wheels being so constructed and arranged that the wheels of each pulley have interlocking and telescoping connection in all adjusted positions of the shiftable wheel members, a belt providing a driving connection between said pulleys, intermediate connecting mechanism between said driven expandible pulley and the bobbins of the machine, a slide, connections between said slide and said shiftable wheels, a rotatable cam operatively connected to said slide for actuating the same, a gear affixed to said cam, and means including a pinion meshing with said gear responsive to the step-by-step adjusting movements of a builder motion of the intermittent type for revolving said cam to effect step-by-step adjustment of said slide through a distance sufficient to adjust the shiftable wheels of both expandible pulleys.

4. In a roving frame, the combination with the bobbins of the machine of a variable speed mechanism for driving the bobbins comprising driving and driven expandible pulleys each consisting of two interfitting conical wheel members one of which is stationary and the other slidale, a V-belt providing a driving connection between said pulleys, a pivoted support sustaining one expandible pulley, a slide, arms connecting said slidale wheel members to said slide for moving both slidale wheel members together when said slide is advanced to vary the working diameters of both expandible pulleys simultaneously, and means including a cam for imparting intermittent step-by-step adjusting movement in the same direction to said slide to regulate the effective working diameters of both of said expandible pulleys.

5. In a roving frame, the combination with the bobbins of the machine of a variable speed mechanism for driving the bobbins comprising driving and driven expandible pulleys each consisting of two interfitting conical wheel members one of which is stationary and the other slidale, a V-belt providing a driving connection between said pulleys, a pivoted support sustaining one expandible pulley, a slide, arms connecting said slidale wheel members to said slide for moving both slidale wheel members together when said slide is advanced to vary the working diameters of both expandible pulleys simultaneously, and means including a cam for imparting intermittent step-by-step adjusting movement to said slide to regulate the effective working diameters of both of said expandible pulleys, one of said arms being swingable on said slide laterally of the slidale wheel member, said swingable arm being bifurcated and having a loose connection with the slidale wheel member to permit adjustment of the lower shaft, and means including a cam manually operable for raising said lower shaft and the expandible pulley thereon from an operative position to an inoperative position, and vice versa, to effect the disconnection and connection of said driving belt with the lower expandible pulley.

6. In a roving frame, the combination with the bobbins of the machine of a variable speed mech-

anism for driving said bobbins comprising driving and driven expandible pulleys each formed of two wheel sections one of which is fixed and the other wheel section shiftable toward and away from the fixed wheel section, a belt providing a driving connection between said expandible pulleys, a cam, means for intermittently actuating said cam to produce step-by-step adjustment of both shiftable wheel sections simultaneously relative to their respective fixed wheel sections to vary the effective working diameter of the pulleys and regulate the speed ratio therebetween, and intermediate connecting mechanism whereby the rotation of said driven expandible pulley is communicated to the bobbins of the machine.

7. In a roving frame, the combination with the bobbins of the machine of a variable speed mechanism for driving said bobbins comprising driving and driven expandible pulleys each formed of two wheel sections one of which is fixed and the other wheel section shiftable toward and away from the fixed wheel section, a belt providing a driving connection between said expandible pulleys, means for adjusting both shiftable wheel sections simultaneously relative to their respective fixed wheel sections to vary the effective working diameter of the pulleys and regulate the speed ratio therebetween, intermediate connecting mechanism whereby the rotation of said driven expandible pulley is communicated to the bobbins of the machine, a cam, a stop member on said cam, and means engaged by said stop

member and operable thereby upon rotation of said cam to a predetermined position for actuating the automatic stop-motion mechanism of the machine.

8. In a roving frame, the combination of two parallel shafts, one a driving shaft and the other a shaft to be driven, two expandible pulleys on one on the driving shaft and the other on the driven shaft, each expandible pulley being formed of two wheel sections one of which is fixed and the other shiftable toward and away from the fixed wheel section, a belt providing a driving connection between said expandible pulleys whereby the driven shaft will be operated by the expandible pulley on the driving shaft, a slide, connections between said slide and said shiftable wheel members of both expandible pulleys, a rotatable cam operatively connected to said slide for actuating the same, means operable by the usual builder motion of the machine for intermittently operating said cam to produce step-by-step adjustment of said slide for adjusting the working diameters of the shiftable wheels of both expandible pulleys, and intermediate connecting mechanism whereby the rotation of said driven expandible pulley is communicated to the bobbins of the machine, said rotatable cam being so shaped as to secure substantially the same variation in the rotational speed of the bobbins that has been produced previously by the use of the prior convex and concave cone drums usually employed for this purpose.

GEORGE E. REPASS.
